[57] **ABSTRACT**

The texturized print includes an image matrix having spaced, molded surface indentations therein. In the method, the softened multi-layer emulsion surface of a photographic color print is pressed into contact with a texturized non-stick surface and hardened so as to mold indentations therein in conformance with the textured surface. In the apparatus, a press means has a textured Teflon surface adapted to be brought into contact with a softened, multi-layer emulsion of a photographic print, so as to mold the emulsion into conformance with the texture of the Teflon surface during the hardening of said emulsion.

TEXTURIZED PHOTOGRAPHIC PRINT, METHOD AND APPARATUS

BACKGROUND OF THE INVENTION

This invention relates to texturized photographic prints and more particularly to texturized color photographic prints, apparatus and method for producing the same.

Texturized photographic prints are preferred, especially for portraits, because a texturized finish reduces gloss, softens pictorial details and produces a shorter range of contrast. In the prior art, a texturized finish has been provided in multilayer emulsion paper used for color prints by cold pressing the developed and dried print into contact with a textured surface. This results, however, in high stressing of the emulsions which crack them, producing a ragged surface which shortens print life and produces an unattractive effect.

SUMMARY OF THE INVENTION

In accordance with the invention, the texturized print comprises a support base carrying a photographic image matrix, said image matrix having spaced molded surface indentations therein. More specifically, the texturized print comprises a multi-layer emulsion photo print paper having molded, substantially stress-free indentations in the outer surface of at least the outer layer of the emulsion without cracks or fissures in the surrounding emulsion.

The process of the invention comprises the steps of bringing a softened, developed multi-layer emulsion of a photographic print into contact with a textured non-stick surface, holding said emulsion under pressure in contact with said surface and hardening said emulsion to mold the texture of said surface into said emulsion.

The apparatus of the invention comprises a support means for carrying a photographic print, a press means mounted adjacent said support and adapted for applying pressure to said print in cooperation with said support means, and said press means having a texturized Teflon (polytetrafluoroethylene) surface member thereon.

In a preferred embodiment, the Teflon surface member includes a fibrous material having a thin coating of Teflon which substantially conforms to the undulations of the fibrous material and provides a textured surface.

BRIEF DESCRIPTION OF THE DRAWING

FIG. 1 is a diagrammatic plan view of a portion of a texturized color print magnified approximately 4.7 times;

FIG. 2 is a diagrammatic plan view of a portion of the print shown in FIG. 1, magnified approximately 15 times;

FIG. 3 is a greatly enlarged sectional view of a photo print representative of that shown in FIGS. 1 and 2; and

FIG. 4 is a perspective view of a texturizing apparatus in accordance with the present invention.

DESCRIPTION OF THE PREFERRED EMBODIMENTS

In FIGS. 1, 2 and 3 a developed photographic print 10, for example, a color photographic print on Kodak Ektacolor Professional paper or the like, is shown having a textured surface 12. In this embodiment, the texture is provided by a first pattern of small rounded depressions or indent 18, interposed within a second pattern of comparatively large rounded indent 20. In-

dents 18 and 20 are molded depressions which are formed in the print emulsion 22 during its transformation from a water-softened or gel state to its hardened or dried state. In contrast to the prior art, this provides a true, three dimensional, textured surface, essentially stress-free, and without cracks or fissures formed in the surrounding emulsion between indentations.

In a preferred embodiment, the texture pattern in the emulsion is weave-like in appearance and is formed by using a Teflon coated woven mesh as a mold or embossing surface. As a result of the technique, indent 18 and 20 are elliptical in shape. Indents 18 are smaller and more shallow than indent 20. The major axis of indent 18 are disposed substantially perpendicular to the major axis of indent 20. This provides an attractive texture pattern. More importantly, however, the concave indentations tend to act as mirrors which provide minute focal points so as to further enhance picture detail.

It should be understood that the indentations of the completed print may be provided by raising the surrounding emulsion rather than depressing indent areas. In actual practice, the original surface is generally both raised at some points and depressed at adjacent points. Hence, the flat surface portions shown in FIG. 3 do not necessarily represent the original level of the emulsion surface. Moreover, these areas will also generally show some convexity depending upon the mold surface.

Many different mold or texturizing designs may be employed but, the non-stick surface of Teflon must be present in order to avoid damage to the wet, sticky color emulsions. While a mold made only of textured Teflon may be employed, a thin coating of this material over a textured non-yielding or hard base material, such as fiberglass, metal or the like, is preferred. The base may take the form of a surface textured plate as well as woven or non-woven fibers.

In a first step of the method of the invention, a print such as that shown in FIGS. 1-3, is formed by bringing the print emulsion 22, while it is in a water-softened or non-hardened state, into contact with an irregular or nodose, non-stick surface of Teflon. Pressure is then applied to the print and the emulsion is hardened to cast or mold the texture of the mold surface into the emulsion.

In the preferred method, a still wet, developed print is dried with its emulsion in pressure contact with a thin Teflon sheet filled with a web of woven fiberglass. For example, a sheet having a thin Teflon surface coating approximately 0.002 inch thick on woven fiberglass is suitable. The weave of the fiberglass is a plain square weave, e.g. 24 strands per inch, employing fiberglass strands of about 0.005 inch in diameter. Each strand is multi-filar. Sheets having too fine a weave or too thick a surface coating of Teflon, such that the weave texture no longer provides an uneven outer surface, will not be suitable.

As shown in FIG. 4, a press 30, having upper and lower supporting plates 32 and 34, may be employed in the wet texture molding of photographic prints. At least one plate, e.g. plate 34, carries a Teflon surface sheet 36 having exposed surface 38 which is patterned with ridges or depressions, or both. Preferably sheet 36 is a fibrous material having a surface coating of Teflon such as that described above. Plates 32 and 34 are joined on each side by a pivotably mounted cam hinge 40. An arm 42 connects the upper plate to each cam 40. Han-

dle 44 is mounted between the extended ends of arms 42. The press is closed by moving handle 44 forward and downward such that cams 40 maintain the press in a closed position.

In operation, a conventional color photographic print is placed in press 30 while its emulsion is in a wet state. For example, the print is placed in the press immediately following the developing process and prior to drying. The emulsion side of the print is placed face down on surface 38 and press 30 is closed and locked. This sandwiches the print between plates 32, 34 and forces the print emulsion into conformance with surface 36. Press 30 is then maintained in its pressure or locked state until the emulsion becomes hardened. The hardening can, of course, occur at room temperature, however, the process can be accelerated by heating the press to a temperature of up to about 200 degrees F. In any case, this operation molds the surface texture of sheet 36 into the print emulsion.

Since the texturizing operation is a true molding or casting, that is, the texture surface is formed by hardening the emulsion in contact with a mold, very low stress is transferred to either emulsion 22 or its supporting base 24. Hence, in contrast to prior art dry texturizing, the finished print is essentially stress and crack free, and any tendency to curl, etc. is diminished, even when plastic base prints are employed. The technique of the present invention results in a substantially nodose surface in the surface of the print, i.e. one having a plurality of protuberances and recesses which form the texturing indentations. The texturing may also be achieved by a mold having depressed areas or indents, that is, an intaglio surface, so as to provide raised portions of the emulsion.

What is claimed is:

1. A method of texturizing a developed color print comprising the steps of bringing a softened, multi-layer emulsion of a photographic print into contact with a polytetrafluoroethylene member having a texture-like surface, applying pressure to said print to force said emulsion to conform to the texture-like configuration of said surface, and hardening said emulsion under said

pressure so as to mold said emulsion in conformance with said texture-like surface.

2. The method of claim 1 including the step of water softening said emulsion prior to contact with said texture-like surface, and drying said print while under said applied pressure so as to harden said emulsion.

3. Apparatus for texturizing a photographic print comprising a polytetrafluoroethylene member having a nodose surface, means for bringing said surface onto contact with the emulsion surface of said print and holding it therewith so as to mold said emulsion into conformance with the nodose configuration thereof.

4. The apparatus of claim 3 wherein said means includes a pair of support members configured to receive a photographic print therebetween, at least one of said members carrying said polytetrafluoroethylene member, and said means additionally including means for bringing said support members together to force said surface into said contact with said emulsion.

5. The apparatus of claim 4 wherein said support members are substantially flat plates adapted to sandwich a photographic print therebetween, said polytetrafluoroethylene member being a thin sheet which is carried on the planar surface of one member, and said pressing means includes a latch means for holding said support plates in a closed position.

6. The apparatus of claim 3 wherein said polytetrafluoroethylene member is a thin coating in conformance with a comparatively less yieldable underlying texture member.

7. The apparatus of claim 6 wherein said underlying member is fiberglass.

8. The apparatus of claim 6 wherein said underlying member is a thin mesh of fibrous material.

9. The apparatus of claim 8 wherein said fibrous material is fiberglass.

10. A textured photographic color print comprising a multi-layer emulsion print having a texture-like emulsion surface formed by hardening said emulsion in contact with a polytetrafluoroethylene member having a texture-like surface.
